UNITED STATES PATENT OFFICE.

PHILEMON O. DICKINSON, OF NEWARK, NEW JERSEY, ASSIGNOR TO UNGER BROTHERS, OF SAME PLACE.

DESIGN FOR A BORDER FOR COMB-BACKS.

SPECIFICATION forming part of Design No. 26,270, dated November 17, 1896.

Application filed October 10, 1896. Serial No. 608,529. Term of patent 31 years.

To all whom it may concern:

Be it known that I, PHILEMON O. DICKINSON, a citizen of the United States, residing at Newark, in the county of Essex and State of New Jersey, have invented and produced a new and original Design for Borders for Backs of Combs and Similar Articles, of which the following is a description, reference being had to the drawing accompanying and forming a part of the same.

The general style of the design is flowered scrollwork, and it is particularly characterized by the outer or border edge of flowers A, extending along the edge or back of the comb, and the border edge of scrolls B, extending

along the inner edge of the border, the ends of the border being left plain. At the middle of the comb the border is left plain, as shown at D, and this plain surface is bounded underneath by the shelf-festoon E.

The essential features of the design are those above set forth.

What is claimed as new is--

The design for borders for backs of combs and similar articles, substantially as described and shown.

PHILEMON O. DICKINSON.
